UNITED STATES PATENT OFFICE.

HERBERT ELLIS SWIFT, OF LOS ANGELES, CALIFORNIA.

OIL-BURNER.

No. 926,780.

Specification of Letters Patent.

Patented July 6, 1909.

Application filed June 30, 1908. Serial No. 441,077.

To all whom it may concern:

Be it known that I, HERBERT ELLIS SWIFT, a citizen of the United States, residing at Los Angeles, in the county of Los Angeles and State of California, have invented new and useful Improvements in Oil-Burners, of which the following is a specification.

This invention relates to oil burners for heating domestic cooking or heating stoves 10 or furnaces and other types of furnaces, the object of the invention being to provide a simple construction of burner which may be easily and conveniently started, which will generate an ample supply of gas or vapor in 15 an economical manner, and which provides for the vent of any excess quantity or pressure of the gas or vapor generated to secure safety in the use of the burner.

With the above and other objects in view, 20 the invention consists of the features of construction, combination and arrangement of parts hereinafter fully described and claimed, reference being had to the accompanying drawing showing a burner embodying my invention in vertical longitudinal section.

Referring to the drawing in detail, 1 designates the body of the burner forming a generating chamber, said chamber preferably comprising a central section 2 and end sections 3 and 4 threaded or otherwise detachably connected so as to permit of their disassembly when occasion requires to clean or repair the parts.

The sections 1 and 3 are preferably tubular 35 in form, the section 3 being closed at its outer end by a head 4 and provided with a depending nipple 5, to receive the upper vertical end of an L-shaped vapor or gas discharge pipe 6 closed at its outer end and provided 40 adjacent thereto in its upper wall with an outlet 7 for the discharge of the vapor or gas. The section 4 of the generator has the general form of an elbow, which curves downwardly and forwardly from the adjacent end of the 45 central section 2 toward the forward end of the pipe 6 and terminates above the latter. In effect, the section 4 constitutes a retort in which the oil is vaporized, said section being provided at its lower end with a contracted 50 basin, chamber or well 8 closed at its lower end and arranged above the outlet 7 of the pipe 6. The upper end of pipe 6 projects into the generating chamber in the form of a guard extension 6^a to prevent any unvaporized oil

which may be in said chamber from passing 55 into said pipe.

Extending longitudinally through the sections 1 and 3 of the generator is an oil feed pipe 9, which extends longitudinally into the upper portion of the section or retort chamber 4 and is formed therein with a downwardly extending discharge portion or nozzle 10 terminating in line with and above the basin or well 8.

In the practical use of the device, the 65 burner, constructed as above described, is disposed within the fire-box of the stove or furnace and suitably supported in position, and the opposite or outer end of the oil feed pipe 9 extends through one of the walls 11 of 70 the body of the stove to the exterior and is externally threaded for connection with a coupling 12 by which it is connected with an oil supply pipe 13 and a safety or vent pipe 14, in which pipes are arranged suitable controlling needle valves 15 and 16. The pipe 13 leads from a storage tank or other source of oil supply located at an elevation for the feed of oil by gravity or coöperating with suitable means for a force feed, as desired, 75 while the pipe 14 extends to a suitable point to discharge any excess gas or vapor passing out of the same from the burner to the atmosphere.

When starting the burner, the valve 15 is 85 slightly opened to permit a small quantity of the oil to flow through the pipe 9 into the cup 8, which is heated by a torch or in any other suitable manner, to effect the conversion of such oil into gas or vapor. This gas or vapor 90 fills the generator and flows outwardly through the pipe 6 and discharges through the outlet 7 at which it is ignited, the flame therefrom playing against the cup 8, so that upon again opening the valve 15 a constant 95 feed of oil in the cup may be secured, which oil will be converted into vapor for a constant supply to the pipe 6 and from thence through the outlet 7 into the fire-box of the stove or furnace. As soon as the burner as a 100 whole is heated sufficiently for the rapid generation of gas, a large amount of vapor discharges through the outlet 7 and this is ignited, forming a body of flames heating the entire area of the fire-box and surrounding 105 the burner, whereby the oil flowing thereinto is quickly converted into vapor and the temperature of the latter maintained at the de-

sired point for ready admixture of the air drawn into the fire-box and ignition when the combustible mixture comes into contact with the flames.

5 By the use of the cup 8, any quantity, large or small, of the feeding oil may be quickly converted into vapor, since the flames from the generated and discharged gas play directly against the same, thus 10 effecting economy in the use of the apparatus for enabling the device to be quickly started in operation and maintained in operation without liability of an undue reduction of pressure from an imperfect application of the 15 flames to the retort. After the apparatus has been started and is in proper working order, the valve 16 is opened to a greater or less extent to permit of the discharge of any excess pressure of gas or vapor which might 20 be liable to cause an explosion. If there should be at any time an excess generation of gas within the chamber 1, the back pressure of the gas or vapor through the oil feed pipe 10 will force the oil back through said pipe 25 into the supply pipe 13, and the gas will therefore vent through the feed pipe into the pipe 14 and thence to the atmosphere. By this means safety is insured under all conditions of service.

30 Having thus fully described the invention, what is claimed as new is:—

1. An oil burner comprising a generating chamber having a depending portion provided with a contracted cup, a vapor supply pipe extending from the opposite portion of the generator and provided with a vapor outlet disposed below and in line with said cup, and an oil feed pipe extending longitudinally

through the generating chamber and having an angularly bent nozzle depending in line 40 with and terminating above said cup.

2. An oil burner comprising a horizontally disposed generating chamber provided at its outer end with a depending portion forming a retort, said retort being formed at its lower 45 end with a depending contracted cup or well, a vapor supply pipe leading from the other end of the generating chamber and extending beneath the cup and provided in proximity thereto with a vapor outlet, and an oil feed pipe extending longitudinally through the generator chamber and having its outer end bent downward to form a nozzle disposed within the retort and arranged in line with and terminating above said cup or well. 50

3. An oil burner comprising a generating chamber having a depending retort provided at its lower end with a cup of reduced area, vapor supply pipe leading from the opposite end of the chamber beneath said well and 60 having a vapor outlet in line therewith, an oil feed pipe extending longitudinally through the chamber and provided at its inner end with a nozzle extending downwardly into the retort and terminating 65 above and in line with the well, oil supply and gas discharge pipes connected with the outer end of said feed pipe, and valves in said supply and discharge pipes.

In testimony whereof I affix my signature 70 in presence of two witnesses.

HERBERT ELLIS SWIFT.
